ENGINE

Allan R. Wurtele, New Roads, La.

Application October 18, 1938, Serial No. 235,551

4 Claims. (Cl. 123—188)

This invention relates to internal combustion engines of the solid fuel injection type and more particularly to valve and fuel injection apparatus therefor.

It is an object of the present invention to provide novel apparatus wherein a valve and fuel injection mechanism of a solid fuel injection engine are combined in a novel manner.

Another object of the invention is to provide a novel valve and guide means therefor in an internal combustion engine.

It is a further object to provide novel means embodying a fuel injection mechanism adapted to guide the valve during the reciprocal travel thereof.

A still further object is to provide novel valve and fuel injection mechanism for an internal combustion engine comprising only a small number of comparatively rugged parts which may be compactly arranged whereby the engine as a whole is greatly simplified, its reliability increased and installation, operation and maintenance costs decreased.

Still another object of the invention is to provide novel valve and fuel injection apparatus comprising a minimum number of moving parts whereby friction and inertia losses are greatly reduced and the mechanical efficiency and adaptability for high speed operation are correspondingly increased.

The above and further objects and novel features of the invention will appear more fully from the following detailed description when the same is read in connection with the accompanying drawing. It is to be expressly understood, however, that the drawing is for the purpose of illustration only and is not intended as a definition of the limits of the invention, reference being primarily had for this latter purpose to the appended claims.

In the drawing wherein like reference characters refer to like parts throughout the several views,

Fig. 1 is a side elevation partly in section and with parts broken away of one cylinder of an internal combustion engine embodying one form of the present invention, and

Fig. 2 is a detail view partly in section and with parts broken away, the section being taken substantially along line 2—2 of Fig. 1.

A single embodiment of the present invention is illustrated, by way of example, as applied to a power cylinder 4 of a two cycle, valve-in-head, solid fuel injection engine, said power cylinder having cooling fins 5 cast integrally therewith and a piston 6 reciprocable therein. A cylinder head 7 comprising a separate casting is securely mounted on cylinder 4 by suitable bolts (not shown) and is preferably provided with an exhaust port 8 concentric with said cylinder and

opening into an exhaust passage 9 extending diametrically through said head.

A novel valve mechanism operable in combination with novel fuel injection and guiding means is provided by the present invention and comprises a minimum number of light moving parts, the same being thereby adapted for efficient and rapid operation on high speed engines, such as aviation engines. As shown, the valve mechanism includes an enlarged head portion 11 and a hollow stem 12, said head portion being adapted to close port 8 to passage 9 by engaging a seat formed in cylinder head 7 at the periphery of said port. The interior of valve head portion 11 and a recess 6' in the upper end of piston 6 cooperate to form a central precombustion chamber 6a when said piston is in substantially top center position (Fig. 1). Stem 12 is provided with a plurality of circumferentially spaced longitudinal slots 13 extending throughout the major portion of the length thereof and is slidably mounted in and guided by the walls of an opening 14 in cylinder head 7, valve 11, 12 being adapted to reciprocate within said opening to control the flow of exhaust gases through port 8.

As a further guide for stem 12 during the reciprocal travel thereof a novel hollow barrel or spindle 15 is mounted concentrically within said stem in close engagement therewith. A plurality of fins or ribs 16 are formed integrally with said spindle, said fins being suitably circumferentially spaced to extend radially from said spindle through slots 13, preferably beyond the periphery of said stem. Thus, in addition to guiding the latter, said ribs also provide an effective cooling means conducting the heat from said valve stem and spindle 15 to the medium surrounding the valve mechanism.

A flange 17 formed integrally with spindle 15, 40 adjacent the base thereof is secured to cylinder head 7 by suitable means, such as bolts 18. The unitary rigid structure composed of said spindle and flange is provided with a series of openings 19 through which the arcuate sections 12' of stem 12 extend, said sections having a close sliding fit with the walls of said openings. A portion of said spindle extends downwardly beyond the base of said flange through opening 14 in the cylinder head, thus providing an added guide for valve stem 12. The length of slots 13 is preferably such that when valve 11, 12 is closed said slots terminate a slight distance beneath the base of flange 17. Novel means carried by spindle 15 are provided for injecting fuel centrally into said precombustion chamber 20 and the annular main combustion chamber formed between cylinder head 7 and piston 6. The fuel is sprayed through an orifice 21 of a nozzle 22, the latter being threaded into the bored-out, lower portion of hollow spindle 15 and having a centrally disposed

bore 23 communicating with said orifice. A conical valve 24 is provided for controlling the fuel flow through said nozzle and is carried by a plunger 25 reciprocally mounted in bore 23 and adapted to shut off the fuel flow by engaging a seat formed at the upper edge of nozzle orifice 21. Valve 24 is normally held in yielding engagement with said seat by suitable resilient means, such as a coil spring 26 mounted within the bore of spindle 15 and interposed between the end of said bore and a spring seat 27, the latter being adapted by direct engagement with the upper face of plunger 25 to transmit the spring pressure thereto.

Bore 23 is connected by a plurality of radial passages 28 with an internal circumferential groove 29 in spindle 15 and said groove is connected in turn by a fuel passage 30 to a conduit 31, said last named fuel passage being bored through the wall of spindle 15, one of ribs 16 and flange 17. Conduit 31 is fed a measured quantity of fuel under pressure at predetermined intervals by a suitable fuel pump (not shown) in a manner well understood in the art. When the fuel pressure in bore 23 is built up to exceed the pressure of spring 26, plunger 25 is moved upwardly away from the valve seat and fuel is injected into the combustion chamber.

Valve 11, 12 is normally held in closed position by the action of suitable resilient means, such as a compressed coil spring 32, interposed between flange 17 and an annular flange 33 fixed to a cap 34 which is threadedly secured to the upper end of stem 12. Cap 34 is provided with a second flange 35 which extends downwardly and engages the outer surface of valve stem 12 to hold arcuate sections 12' of the latter in position. After cap 34 is threaded into operative position the same may be locked against inadvertent or accidental release by a pin 36 inserted into the threaded portion of cap 34 and extending radially through one of slots 13. A rocker arm 37 suitably actuated by the usual cam means (not shown) is adapted to control the movement of valve 11, 12 to open port 8 by engaging the upper surface of cap 34.

In order to facilitate the flow of exhaust gases from the cylinder and prevent the accumulation of exhaust gases in the valve head portion of pre-combustion chamber 6a, a group of circumferentially spaced openings 38 is provided in valve stem 12, said openings constituting a fluid passage from said valve interior to exhaust passage 9 when valve 11, 12 is opened. However, when said valve is closed as shown in Fig. 2, said openings are inoperative as passages being confined in the space between spindle 15 and the walls of opening 14. Thus, a complete scavenging becomes possible when valve 11, 12 is opened since the gases normally trapped in the interior of the hollow valve head are swept out through openings 38 by the upwardly flowing scavenging gases.

There is thus provided a novel valve and fuel injection mechanism operable in combination with the power cylinder of a high speed engine to produce central scavenging and central fuel injection in said cylinder. The mechanism which comprises comparatively few compact, rugged, parts which are light in weight is suited for use on aviation and automobile engines because of its light and reliability and for high speed engines of any class because of the limited number of parts set in motion during operation of the mechanism. The reduction of friction and inertia losses and the increased responsiveness of the moving parts causes a corresponding increase

in operating efficiency of the engine. Furthermore, the provision of guiding fins increases the heat conductivity and emissivity of the mechanism and eliminates the danger of overheating and failure of parts and further produces a substantially uniform temperature over the various moving and stationary parts thereby aiding the mechanical efficiency and smoothness of operation by causing a uniform expansion of all parts.

Although only a single embodiment of the invention has been illustrated and described, it is to be expressly understood that the same is not limited thereto. For example, it will now be apparent to those skilled in the art that some different number of cooling fins than is shown might be utilized and that said fins might be of some greater or lesser length or of a different shape.

Although only a single embodiment of the invention has been illustrated and described, it is to be expressly understood that the same is not limited thereto. For example, it will now be apparent to those skilled in the art that some different number of cooling fins than is shown might be utilized and that said fins might be of some greater or lesser length or of a different shape. The novel valve and fuel injection means may, of course, be employed in other types of engines than the one shown. Various changes may also be made in the design and arrangement of parts illustrated without departing from the spirit and scope of the invention. For a definition of the invention reference will be had primarily to the appended claims.

What is claimed is:

1. In an internal combustion engine a power cylinder having a port therein, a valve for said port having a hollow stem provided with longitudinal slots extending to one end thereof, a unitary guide member in said valve stem, and fins integral with said member extending through said slots, said member being supported by said cylinder.

2. In apparatus of the class described, a valve having a head portion and a hollow stem, the latter having at least one longitudinal slot therein extending to the end thereof opposite said head, means having an annular groove for receiving said end of the stem, one wall of said groove having threaded engagement and the other having sliding engagement with said stem, a unitary guiding element slidably engaging the inner wall of said stem and having a portion extending outwardly through said slot, and means for fixedly securing said last-named portion to a stationary support.

3. In apparatus of the class described, a valve having a head portion and a hollow stem, the latter having at least one longitudinal slot therein extending to the end thereof opposite said head, and means having an annular groove for receiving said end of the stem, one wall of said groove having threaded engagement and the other having sliding engagement with said stem.

4. In apparatus of the class described, a valve having a head portion and a hollow stem, said stem having a plurality of circumferentially spaced longitudinal slots therein extending to the end thereof opposite said head, a guiding element slidably engaging the inner wall of said stem and having cooling fins extending outwardly through said slots, and means associated with said fins for securing said element to a stationary support.
